T. H. GOLDRING,
SELF SEALING PACKING CASE.
APPLICATION FILED MAR. 9, 1914. RENEWED NOV. 22, 1915.

1,183,002.

Patented May 16, 1916.

UNITED STATES PATENT OFFICE.

THOMAS H. GOLDRING, OF TORONTO, ONTARIO, CANADA.

SELF-SEALING PACKING-CASE.

1,183,002.

Specification of Letters Patent.

Patented May 16, 1916.

Application filed March 9, 1914, Serial No. 823,301. Renewed November 22, 1915. Serial No. 82,924.

To all whom it may concern:

Be it known that I, THOMAS H. GOLDRING, a subject of the King of Great Britain, and resident of the city of Toronto, county of York, Province of Ontario, in the Dominion of Canada, have invented certain new and useful Improvements in Self-Sealing Packing-Cases, described in the following specification and illustrated in the accompanying drawings, that form part of the same.

The principal objects of the invention are, to reduce the cost of packaging comparatively light packages of merchandise for trans-shipment, to eliminate a great deal of the pilfering that goes on while freight is in transit through the packages being opened and a portion of the contents removed and the box then closed.

20 A further object is to materially reduce the cost of packaging reducing the weight and bulk of the cases.

A still farther and very important object is to enable the storing of packages in knock down form, thereby obviating many of the difficulties at present existing where the ordinary form of wooden box is used for shipment of merchandise.

The principal feature of the invention consists in the novel formation of a shipping case wherein the end closure is automatically locked from the inner side on being placed in position to close the case.

In the drawings, Figure 1 is a perspective view of a casing constructed in accordance with this invention showing the cover removed. Fig. 2 is a vertical sectional view of my improved form of case showing the bottom closure in its locked position and the top closure about to be inserted.

Like numerals of reference indicate corresponding parts in each figure.

Referring to the drawings, 1 is the body of the case which is preferably formed of fiber board of a suitable thickness, creased to form the corners, having the ends secured together to form a rectangular ¹ x open at the ends. The case thus formed is collapsible and folds down into a flat shape.

50 2 are metal strips formed of sheet metal having the outer edge bent over presenting an interlocked portion 3. These strips are secured to the inner sides of the walls of the case by means of small rivets, which are here shown as being the ordinary straight rivets or other fasteners, but

used. The interlocked hook shaped edges of the strips 2 are spring held against the inner sides of the box by the natural spring of the metal strip and the rounded upper or outer edge presented will not offer an objectionable obstruction.

55 3 are the end closures formed of a sheet of fiber board adapted to fit snugly into the ends of the case 1 and these have secured to their inner side the angularly shaped sheet metal strips 6, the inwardly extending flanged portions 7 of which are formed with the edge bent over to form a hook shape extremity 8. The flanges 7 being flush with the edges of the cover fit snugly against the inner side walls of the casing 1 and when the covers are inserted in place the round edge of the hook shaped edge engages the rounded edge of the strips 2 springing the 75 said strips 2 outwardly until the hooked edges of the cover strips pass the hook edges of the strips 2 when the inward spring of the said strips 2 causes them to spring inwardly, thus interlocking the hook shaped 80 edges and consequently the cover, locking it firmly in place.

In the use of this case, the open ended body portion is kept in stock in a knock down form and when required to be packed 85 it is opened out and one of the ends is inserted in place pressed inwardly until the locking strips engage each other to secure it in position. The goods are then placed within the case and when filled the cover 5 90 is inserted and pressed inwardly until the locking strips engage in locking contact as previously described.

When a case is thus closed both ends are locked securely and inseparably against removal and they cannot be opened without destroying the box. This feature is highly desirable as it is often found that packing cases are tampered with in trans-shipment and part of the contents removed, the covers being again replaced. Tampering with the contents of the cases in trans-shipment will thus be entirely obviated.

A very important feature of this invention is that it renders the box strong and durable and reinforces the fiber board or straw board from which it is made in such a manner as to allow it to be used in carrying packages of considerable weight. Furthermore it is not required that wood strips be used in place of this kind as the metal angle strips used on the cover and necessary

- for the locking of said cover and bottom in place, fulfil the function of rigid reinforcement which prevents the cover from buckling or bending. In addition to this the 5 strips secured to the sides of the case and having an inwardly bent edge form strengthening reinforcements for the case which will prevent the box sides from bulging or being pressed out of shape.
- 10 The advantages to be considered are thus very material the feature of lessening risk in transportation and loss through various causes, the locking device is very simple requires no skill whatever in securing the 15 cover, it being merely necessary to insert the cover and push it into place and when pressed home will lock automatically. A great saving in time of a packer is thus obviated and the extra expense of wood, bales, 20 etc. is avoided, as well as presenting a much better appearance outside with no projecting portion and a smooth interior which will not interfere with the goods. The lock strips in the casing are arranged preferably 25 a short distance in from the edge so that when the covers are placed in position they will be arranged a short distance from the outer edge of the sides of the casing, thus adding considerably to the strength and 30 providing an edge for the shippers handling the boxes to grip the same so that they will not be as liable to let them fall.

What I claim as my invention is:—

1. A packing case of thin flexible material 35 open at the end, reinforcing strips of sheet metal secured to the inner walls of said casing and extending transversely thereof adjacent the open end, and locking means projecting from the inner surface of 40 said cover to engage said strips, when the cover is in place in inseparable locking engagement.
2. A packing case of thin flexible material 45 open at the end, reinforcing strips of sheet metal secured to the inner walls of said case and extending transversely thereof and adjacent to the open end having the outward free edges formed in hook shape, a cover adapted to close said case, and hooked 50 members secured to the inner surface of said

cover adapted to extend into said case to engage the hook-shaped edges of the locking strips within the case in inseparable locking engagement.

3. A packing case of this flexible material 55 open at the end, sheet metal reinforcing strips secured to the inner walls of said case adjacent to the open end and extending transversely thereof, said strips having their outward free edges bent into hook 60 shape, a cover adapted to be inserted into the open end of said case, and sheet metal reinforcing strips projecting inwardly therefrom, said cover strips having their free edges formed in hook shape to engage 65 the strips within the case in inseparable locking engagement.

4. A packing case of thin flexible material open at the end, a cover having flanges adapted to extend into the case, said flanges 70 having inwardly turned hooked extremities, and sheet metal strips secured to the inner walls of the case adjacent the open end and extending transversely thereof, said strips being formed with outwardly turned hooked 75 edges adapted to spring into locking engagement with the hooked cover flanges and to seal the cover in place.

5. A packing case of thin flexible material open at the end, a cover adapted to be inserted in said open end and having right angularly arranged flanges extending around the edges, said flanges having their inner edges formed with inwardly turned hook shaped extremities, sheet metal strips secured to each of the inner walls adjacent to the open end and extending transversely thereof and substantially the entire width of said walls, said strips having the outward edges bent outwardly toward the wall 90 of the case in hook shape to engage the cover flange hooks in inseparable locking engagement.

Signed at the city of Toronto, county of York, Ontario, Canada, this 2nd day of 95 March 1914.

THOMAS H. GOLDRING.
